US0D1025790S

(12) **United States Design Patent** (10) **Patent No.:** **US D1,025,790 S**
(45) **Date of Patent:** **** May 7, 2024**

(54) **CLOCK**

(71) Applicant: **Cartier International AG**, Steinhausen (CH)

(72) Inventor: **Raphael Mechelany**, Geneva (CH)

(**) Term: **15 Years**

(21) Appl. No.: **35/517,134**

(22) Filed: **Mar. 10, 2023**

(80) **Hague Agreement Data**

Int. Filing Date: **Mar. 10, 2023**

Int. Reg. No.: **DM/227536**

Int. Reg. Date: **Mar. 10, 2023**

Int. Reg. Pub. Date: **May 12, 2023**

(51) **LOC (14) Cl.** **10-01**

(52) **U.S. Cl.**

USPC **D10/26**; D10/37
